GEORGE W. STOUT AND JOHN C. RICHARDSON, OF NEWARK, NEW JERSEY, ASSIGNEES TO THEMSELVES, JAMES DAVIS, JR., AND SAMUEL R. HAWLEY, ASSIGNEES TO SAID STOUT, JAMES H. PRENTICE, SAID DAVIS, JR., AND HAWLEY.

Letters Patent No. 84,915, dated December 15, 1868.

IMPROVEMENT IN HAT-IRONING MACHINES.

The Schedule referred to in these Letters Patent and making part of the same.

To all whom it may concern:

Be it known that we, GEORGE W. STOUT and JOHN C. RICHARDSON, both of the city of Newark, in the county of Essex, and State of New Jersey, have made certain Improvements in various parts of the Hat-Finishing Machine for which a patent was issued to GEORGE W. STOUT, JOHN C. RICHARDSON, JAMES DAVIS, JR., and SAMUEL R. HAWLEY, as assignees of GEORGE W. STOUT and JOHN C. RICHARDSON, said patent bearing date December 3, 1867; and we do hereby declare the following, taken in connection with the drawings which accompany and form part of this specification, to be such a description of our improvements as to admit of construction and use therefrom.

Our newly-invented improvements consist, mainly, in the parts employed in ironing the brim, and in the mechanical provisions for manipulating the iron used for the side of the crown.

Figure 1 shows the improved machine in perspective.

Figure 2 is an edge and front view of the vibratory arm and its attachments, with the hollow face-plate on which the brim is finished.

Figure 3 is the platform-top of the main frame and the movable supports for two irons, the bearings and irons removed therefrom.

The same letters refer to the same parts in each.

The main stand, of which fig. 3 shows the top, is designated by A.

Below, in front, is the main shaft B, upon which are the small pulley C, the bevel-gear Z, the main driving-pulley E, and the two swinging arms, F and G.

Another pulley, D, thereon, may serve to drive the shaft which carries the hat-block, for a purpose herein-after stated, and a loose pulley, similar to E, may preferably also be put on this shaft.

Upon the top of the swinging arm F there is a platform that turns in any direction, in a horizontal plane, upon the top of a shaft, y, which has its bearings on the arm.

Under the platform, and on the upper end of shaft y, is a small wheel, which turns (by an intermediate gear, if desired,) the small wheel and stud a, on the top of which, above the platform, is a bevel-wheel, which drives a corresponding bevel-gear on the shaft x, to which is attached the iron designated as No. 1.

On the back of the arm F, near its lower end, may be attached a projecting lever-bar, upon which may be suspended a pressure-weight, w, adjustable at pleasure, or a spring or elastic band may be substituted therefor.

This swinging arm is arranged to slide upon the main shaft B, the bevel-gear Z thereon sliding easily, with its key, in an elongated key-seat on the shaft.

A bent lever, with a handle, u, may, if desired, be employed, having its rear lower end pivoted to the back bar of the main frame, (not shown,) and being connected to the arm, near its bearings on B, such lever

serving to move the arm back or forth upon the shaft with facility.

Two handles, s and t, may also, if desired, be attached to the platform, near its extremities, for the purpose of regulating the position of the iron No. 1 and its frame relatively to the hat-body.

A second swinging arm or vibratory frame, G, which has its bearings also on the main shaft B, has on its upper end other bearings for the shaft q, fig. 2, upon which shaft are a hollow face-plate, H, the hand-wheel, (if desired,) and the small pulley p; the latter driven whenever needed and at option, by the large pulley D on the main shaft B.

The belt upon these pulleys D and p runs loose while the hat is being ironed, but is tightened, as hereafter mentioned, when the hat-body is being sponged prior to ironing.

The small pulley C on the main shaft drives the shaft n, upon which shaft a bevel-wheel, m, or other shifting-device, slides easily, and on which is also the gearing that drives the face-plate H whilst the hat is being ironed.

The sliding bevel-wheel m turns a shaft in a long bearing attached to a support, shown detached at t, fig. 3. Upon the end of this shaft is iron No. 2.

Iron No. 3 is a curved hollow box, its broadest side being presented to the hollow face-plate, its lower or concave side being bevelled or acute-angled at its inner edge, as shown, so as to iron the brim close up to the crown of the hat.

This box is secured to a piston-rod, that allows of its turning freely, to press equally on the brim.

The piston-rod enters a small cylinder, J, and has coiled upon it a spiral spring (not needed to be shown) that presses it outward and towards the hat when not held back and away from the hat by the handle K.

The force of the spring can be adjusted by a screw-cap on the top of the cylinder.

In fig. 3 are shown the supports for the bearings of irons Nos. 2 and 3.

The tops of these supports, for convenience of the required angular adjustments of the irons relatively to the hat-body, are made circular, with a bolt or bolts and slots to confine the bearings to them.

These supports slide freely upon two round bars, the one holding iron No. 2 being drawn towards the crown, and pressed thereupon by a cord attached to the bottom of the support, which cord, passing over a pulley in the platform, has a suitable weight, h, suspended upon it, resembling in this latter respect the arrangement shown in our above-named patent.

The iron No. 3 is drawn towards the face-plate by a stiff spiral spring, g.

Iron No. 2 may be drawn back and held from work by a small crank, f, held at its dead-point by the bar f', the handle e serving for this purpose.

Iron No. 3 may be forced and held back in the same manner by the handle *d*.

We employ flexible tubes to conduct the gas through hollow shafts to the interiors of the irons Nos. 1 and 2, and directly to the interiors of No. 3 and of the face-plate *H*, suitable vents being provided for the air from their interiors, and for the admission of the air needed for combustion.

The operator takes hold of an ordinary hand-wheel, *I*, or of the frame *G*, and pulls the face-plate forwards into the position shown by the dotted lines in fig. 2.

He next secures the hat-block, with the hat thereon, to the face-plate *H*, attaching it to the central pointed screw, or to some other fitting appendage thereon, and brings down the tightener to the belt, and then proceeds to sponge the hat preparatory to ironing.

He then takes up the tightener, puts up the arm *G*, and the face-plate *H* then comes into operative connection with its driving-gear on shaft *n*.

By turning down the handle *d*, and turning upwards the handle *e*, iron No. 3 is brought into position to act upon the brim, and iron No. 2 to act upon the tip or crown.

Then, by laying hold of handles *t* and *s*, (if they be used,) and putting his knee to the bent lever *u*, or to the arm *F*, if the lever be not employed, he can twist, turn, and move iron No. 1 into any needed position, and can consequently iron round crowns with the same fa-

cility that he can iron flat ones, the machine being thus easily adjustable, and adapted for operating upon any form of crown.

We claim—

1. The swinging arm *F*, supporting a platform, carrying a revolving iron and its driving-mechanism, when the platform is arranged to be adjusted for ironing the sides of hat-crowns, substantially as set forth.

2. The hollow face-plate *H*, constructed with teeth on its periphery, and arranged to be swung into or out of gear with its driving-mechanism, substantially as described.

3. The hollow-box iron No. 3, constructed with an acute-angled face on its concave side, combined with the hollow face-plate *H*.

4. The combination of the hollow face-plate *H* and hollow-box iron No. 3, when the latter is arranged with its shank or piston playing in a cylinder and under spring-pressure.

5. The combination of the slides which carry the boxes or bearings for the irons, with the slotted adjustable plates which support the irons.

GEORGE W. STOUT.
JOHN C. RICHARDSON.
